(57) **CLAIM**

I claim the ornamental design for an outsole for a shoe, as shown and described.

DESCRIPTION

FIG. 1 is a bottom plan view of an outsole for a shoe showing my new design;

FIG. 2 is a right side view thereof;

FIG. 3 is a left side view thereof;

FIG. 4 is a front view thereof;

FIG. 5 is a rear view thereof; and,

FIG. 6 is an enlarged perspective view of the area labeled "6" in FIG. 1.

The broken line forming an oval shape in FIG. 1 represents an internal boundary of the design, with the line itself and the area within, forming no part of the claim.
